PLAYGROUND APPARATUS OR THE LIKE

Donald D. Hock, Herrin, and Robert E. Feigenbaum
and Erwin N. Korte, Carbondale, Ill., and William R.
Baynes, Palos Verdes Peninsula, Calif., assignors to
Mattel, Inc., Hawthorne, Calif.

Filed Jan. 7, 1971, Ser. No. 104,824

Term of patent 14 years

Int. Cl. D21—03

U.S. Cl. D34—5

Fig. 1

Fig. 2

Fig. 3

FIG. 1 is a perspective view of a playground apparatus or the like embodying our design;
FIG. 2 is a right side view of same;
FIG. 3 is a front view thereof;
FIG. 4 is a top view thereof;
FIG. 5 is a bottom view thereof;
FIG. 6 is a rear view of same; and
FIG. 7 is a left side view.

We claim:
The ornamental design for a playground apparatus or the like, as shown and described.
